Patented May 30, 1916.

FIG. 1.

FIG. 2.

FIG. 3.

Inventor:
Henry Charles Jenkins.
By: H. C. Jenkins, atty.

UNITED STATES PATENT OFFICE.

HENRY CHARLES JENKINS, OF LONDON, ENGLAND.

ELECTROLYTIC CELL.

1,185,407.

Specification of Letters Patent. Patented May 30, 1916.

Application filed November 9, 1915. Serial No. 60,553.

To all whom it may concern:

Be it known that I, HENRY CHARLES JENKINS, a subject of the King of England, residing at 804 Salisbury House, London Wall, London, England, (whose post-office address is 804 Salisbury House, London Wall, London, England,) have invented certain new and useful Improvements in Electrolytic Cells, of which the following is

10 a specification.

The present invention relates to electrolytic cells for the decomposition of solutions such as aqueous solutions of alkaline chlorides or nitrates and similar purposes and 15 applies more particularly to cells in which the decomposition is effected without the use of a porous diaphragm separating the liquids lying around the cathode and anode respectively.

20 The invention is specifically applicable to cells of the "bell" type and to cells such as are described under my previous Patent No. 1150370 and refers more particularly to improvements in that part of the cell 25 which is outside of the "bell" and is usually the cathode side. But the electrical connections can be reversed for some usages without affecting the invention and this side for such usages would then become the anode.

30 The invention consists broadly in the provision of means by which the electrolyte around the electrodes (hereinafter called "the cathodes") situated outside the "bells" of nondiaphragmic cells, can have the electrolytic action concentrated upon the immediate neighborhood of these electrodes and the products of the action finally withdrawn without at any time unduly disturbing the general horizontal stratification of 35 the cell.

40 The invention partly consists in an improved form being given to the outer vessel of the cell whereby its floor is formed into a series of corrugations of sawtoothed or of 45 curved form, the width or "pitch" of such corrugations being such that the crest of each corrugation shall come under one of the "bells" that contain the anodes. These "bells" will usually be of an elongated shape 50 and the corrugations will thus lie transversely across the floor of the external cell. The valleys between the crests form receptacles for electrolyte around the cathodes to be now described and in which that 55 electrolyte can descend in more or less horizontal stratification from the neighborhood

of the open base of the "bell" to the cathode and to its outlet for the products of the electrolytic action. The invention also partly consists in an improved form given to the 60 cathode. The cathodes are made of the general form of two or more pairs of superimposed approximately vertical plates with a central space between the plates forming each pair. All the vertical plates are 65 mounted upon a suitable conducting support by which connection can be made to a bus bar. Each plate of the pair is arranged at a slightly increasing distance the one from the other as compared with the 70 distance between the plates of the pair next to them so that the plates of successive pairs are arranged *en échelon* and a space is left between them through which gases can 75 pass, when these are evolved on the active 80 surface of the cathode, and through which in all cases a film of liquid can creep as by the action of the gases or else by virtue of any difference in density between the original electrolyte and the products of the electrolytic action. In this manner a local circulation is favored in the immediate neighborhood of the cathode that while involving the liquid lying between the plates of the cathode itself does not unduly interfere 85 with the general stratification of the electrolyte in the cathode portion of the cell proper.

The invention further consists in the arrangement of the cathode above the lower 90 part of the valleys of the floor of the outer case of the cell and the connection of the said lower part with an outlet from which the products are finally discharged by direct displacement as by the supply of fresh 95 electrolyte in the neighborhood or interior of the "bell."

Figure I represents a transverse section across a series of parallel anodes and cathodes. Fig. II represents a longitudinal section along the center of one form of the composite cathode. Fig. III represents a plan view of one form of the cathode.

The case is taken for illustration where the active surface of the anode is approximately horizontal and that of the cathode is vertical.

A A are the anodes; B B are their containing "bells"; C C are the cathodes; D is one form of inlet to the cell but any other 110 form may be adopted.

e e is the curved floor of the outer case E

of the cell that is formed of any suitable material and which is shaped into valleys and ridges substantially as shown and already described with a groove *f* toward which the interior of the cathode is directed and which communicates with the outlet *g* from the cathode side of the cell.

The actual surface of the cathodes is formed on pairs of plates such as C' C² and 10 C³ C⁴ and C⁵ C⁶ suitably supported in a conducting support such for instance as the plate *m* with tongues *n* *n*, on which distance pieces *h* *h* and the plates C' C² C³ C⁴ C⁵ C⁶ can be riveted or otherwise suitably 15 supported and through which communication can be made to the electrical bus bar by means of the prolongation *j*. Three such pairs of plates are shown but the number and dimensions can be varied as is required 20 by special considerations. They are however always placed *en échelon* with a gap between the several plates so as to permit the film of liquid or film of liquid with gases when the electrolyte is such that these 25 are evolved to pass in their particular directions. This direction will vary according to the chemical character and concentration of the particular electrolyte in use.

When the electrolytes are such that gases 30 are evolved during electrolysis I provide covers to the cathodes such as *k* in which these gases can be collected and conducted by pipes *l* to any suitable reservoir and utilized but in some cases as when electrolyzing 35 nitrates these covers are not necessary.

The action of the cathode described is as follows:— The electrolytic and local chemical actions at the surface of the cathode give rise to a film of product generally of different density to that of the original electrolyte 40 and which tends to move in a vertical plane over the surface of the plate. In some cases it also gives rise to the evolution of a film of gaseous products. These various films 45 pass into the interior of the composite cathode, the gases (if any) rise to the top of the same while the liquid produced tends to collect toward the lower part of the cathode if denser than the original or toward 50 the upper part of the same if lighter, and when the liquid is discharged from the cathode outlets this liquid will be from the interior of the cathode and be the liquid that has remained longest under the electrolytic 55 action.

Having fully described my invention,

Copies of this patent may be obtained for five cents each, by addressing the "Commissioner of Patents, Washington, D. C."

what I claim and desire to secure by Letters Patent is:—

1. An electrolytic cell of the indicated type comprising a cell and a plurality of 60 bell-shaped tops thereto each containing one of the electrodes, a floor to the outer case of the cell, a series of ridges, valleys and grooves formed in the said floor and corresponding to the number of bells with which 65 the cell is provided, an outlet connected to each of said grooves, and a second electrode adjacent to each of said outlets.

2. An electrolytic cell of the indicated type comprising a cell and a plurality of 70 bell-shaped tops thereto each containing one of the electrodes, a floor to the outer case of the cell, a series of ridges, valleys and grooves formed in the said floor and corresponding to the number of bells with which 75 the cell is provided, an outlet connected to each of the said grooves, and a plurality of second electrodes formed of plates placed vertically *en échelon* with gaps between the 80 edges for the passage of films of products from electrolysis and spaces behind them for the return and circulation of liquid.

3. An electrolytic cell of the indicated type comprising a cell and a plurality of 85 bell-shaped tops thereto each containing one of the electrodes, a floor to the outer case of the cell, a series of ridges, valleys and grooves formed in the said floor and corresponding to the number of bells with which 90 the cell is provided, an outlet connected to each of the said grooves, and a plurality of second electrodes formed of plates placed vertically above the grooves in the cell floor 95 *en échelon* with gaps between the edges for the passage of films of products from electrolysis and spaces behind them for the return and circulation of liquid.

4. An electrode comprising a plurality of plates placed vertically *en échelon* with gaps between the edges for the passage of films of 100 products from electrolysis and spaces behind them for the return and circulation of liquid.

In testimony whereof I have hereunto set my hand in presence of two subscribing 105 witnesses this twenty-first day of October, 1915.

HENRY CHARLES JENKINS.
